(57) **CLAIM**

The ornamental design for a magnetic clip, as shown and described.

DESCRIPTION

FIG. 1 is a top perspective view of a magnetic clip embodying my design;

FIG. 2 is another top perspective view of the magnetic clip shown in FIG. 1;

FIG. 3 is yet another top perspective view of the magnetic clip shown in FIGS. 1 and 2;

FIG. 4 is a top plan view of the magnetic clip shown in FIGS. 1-3;

FIG. 5 is a side elevation view of the magnetic clip depicted in FIGS. 1-4, with the opposite side elevation view being a mirror image thereof;

FIG. 6 is an end view of the magnetic clip depicted in FIGS. 1-5, with the opposite end view being a mirror image thereof;

FIG. 7 is a perspective view of the magnetic clip shown in FIGS. 1-6 in an environment of use;

FIG. 8 is an alternative perspective view of the magnetic clip as depicted in FIG. 7;

FIG. 9 is an alternative perspective of the clip as depicted in FIG. 8;

FIG. 10 plan view of the magnetic clip as shown in FIGS. 8 and 9, with the opposite plan view being a mirror image thereof;

FIG. 11 is a side elevation view of the magnetic clip as depicted in FIGS. 8-10; with the opposite side elevation view being a mirror image thereof;

FIG. 12 is an end view of the magnetic clip as depicted in FIGS. 8-11; and,

FIG. 13 is an end view of the magnetic clip opposite that shown in FIG. 12.

The dash-dash broken lines define the bounds of the claimed design and form no part thereof. The long dash-dash-dash broken lines in FIG. 7 depict environmental structure and form no part of the claimed design.
